DESIGN FOR A CIGARETTE CASE

Dorothy H. Treganowen, San Francisco, Calif.

Application December 24, 1943, Serial No. 112,084

Term of patent 3½ years

(Cl. D85—2)

To all whom it may concern:

Be it known that I, Dorothy H. Treganowen, a citizen of the United States of America, residing in the city and county of San Francisco, State of California, have invented a new, original, and ornamental Design for a Cigarette Case, of which the following is a specification, reference being had to the accompanying drawing, forming part thereof.

Fig. 1 is a perspective view of a cigarette case in open position showing my new design; and

Fig. 2 is a perspective view of the same in closed position.

I claim:

The ornamental design for a cigarette case, as shown.

DOROTHY H. TREGANOWEN.
